DESIGN FOR A BRASSIÈRE

William Rosenthal, New York, N. Y., assignor to Maiden Form Brassière Company, Inc., New
York, N. Y., a corporation of New York

Application September 23, 1936, Serial No. 64,982

Term of patent 14 years

To all whom it may concern:

Be it known that I, William Rosenthal, a citizen of the United States and residing at 115 Central Park West, in the Borough of Manhattan, city, county, and State of New York, have invented a new, original, and ornamental Design for a Brassière, of which the following is a specification, reference being had to the accompanying drawing, forming part thereof.

Referring to the drawing, it will be found that:

Fig. 1 is a front perspective view of a brassière, showing my new design; and

Fig. 2 is a rear perspective view of the brassière shown in Fig. 1.

I claim:

The ornamental design for a brassière, as shown.

WILLIAM ROSENTHAL.
